UNITED STATES PATENT OFFICE

128,975

DESIGN FOR A HEATING STOVE CASING

John A. Dahlstrom, Bay Village, Ohio, assignor to
Perfection Stove Company, Cleveland, Ohio, a
corporation of Ohio

Application April 26, 1940, Serial No. 91,978

Term of patent 14 years

To all whom it may concern:

Be it known that I, John A. Dahlstrom, a citizen of the United States, residing at Bay Village, in the county of Cuyahoga and State of Ohio, have invented a new, original, and ornamental Design for a Heating Stove Casing, of which the following is a specification, reference being had to the accompanying drawing, forming part thereof, and wherein Fig. 1 is a front elevation, Fig. 2 a side elevation, and Fig. 3 a plan view of a heating stove casing showing my new design. The side opposite that shown in Fig. 2 is the

same as the one revealed therein. The dominant features of my design reside in the portions shown in full lines.

The portions of the panels that extend across the sides and about the front corners of the stove casing between the top member and the base thereof, as outlined by dot-and-dash lines, represent conventional grille areas.

I claim:

The ornamental design for a heating stove casing, as shown and described.

JOHN A. DAHLSTROM.
